DESIGN FOR AN ENVELOPE FOR PAPER MONEY

John J. Reinhold, Marietta, Pa.

Application November 23, 1932. Serial No. 46,133

Term of patent 14 years

To all whom it may concern:

Be it known that I, JOHN J. REINHOLD, a citizen of the United States, and a resident of Marietta, county of Lancaster, State of Pennsylvania, have invented a new, original, and ornamental Design for Envelope for Paper Money, of which the following is a specification, reference being had to the accompanying drawing forming a part thereof.

The figure represents a front elevation of an envelope showing my new design, the flap being open.

The four corners of the envelope and the envelope base around the dollar mark are cut out, providing openings through which portions of a bank note or other articles placed therein are visible.

The envelope has no appreciable thickness.

I claim:

The ornamental design for an envelope for paper money substantially as shown and described.

JOHN J. REINHOLD.
